SUPPORTING DEVICE

Josef C. Tenke, Detroit, Mich.

Application November 22, 1933, Serial No. 699,184

4 Claims. (Cl. 24—3)

This invention relates to a supporting device and is illustrated as embodied in a pocket supporting device adapted to suspend a key ring in a pocket above the bottom thereof.

5 An object of the invention is to fasten the device on the inside of a pocket and secure it in position by external fastening means.

Another object of the invention is to provide a supporting device having relatively movable parts which, when in one position, permit the device to

10. which, when in one position, permit the device to be engaged with its fastening means and when in another position prevents separation of the device and its fastening means.

A further object of the invention is to provide a fastening means which protects the ends of the supporting member which are preferably pointed to readily pierce through the pocket for engagement with the fastening means.

Other objects and advantages of the invention will more fully appear from the following description taken in connection with the accompanying drawing, in which:

Fig. 1 is a perspective view illustrating an embodiment of the invention.

25 Fig. 2 is a sectional view showing a device received but not clamped on a fabric member.

Fig. 3 is a rear view of the device shown in Fig. 2.

Fig. 4 is a view corresponding to Fig. 2 showing the device clamped on the fabric member.

Fig. 6 and 7 are views illustrating modified forms of the invention.

3.5 In the drawing the device consists of two members 12 and 13 joined together.

bers 10 and 12 pivoted together as at 14 intermediate their ends. The member 12 in the form shown consists of a wire looped to form a back-

shown consists of a wire looped to form a hook portion 16 at one side of the pivot 14, and a head portion 18 at the opposite side of the pivot 14. This member has been shown in the form of a continuous loop but if desired it may be made

continuous loop but if desired it may be made having two ends which may or may not be joined together. The member 10 is also shown as formed from bent wire, the intermediate portion of which is bent back upon itself upon the opposite sides.

is bent back upon itself upon the opposite sides of the hook member 16 to the lower portion of the head 18 where the wire is looped around the lower portion of the head 18 to form a means for swing-

50 portion of the head 10 to form a means for swinging the member 10 on the member 12. The free ends 22 of the wire extend upwardly beyond the pivot 14 and are slightly curved, the ends of which are pointed to pierce through a fabric material illustrated at 24. Thus it will be understood that I have provided two members pivoted, dis-

the centers intermediate their ends, one member having a hook portion at one end and a head portion at the opposite end; the other member having a guard portion 26 at one end and at its opposite end a pair of pointed projections. The distance between the vertical arms of the guard portion 26 is slightly less than the width of the hook portion 16 so that the hook portion is frictionally held between the arms of the guard portion 26.

The device is intended to be inserted in the pocket of a garment, opened as shown in Fig. 2. The pointed projections 22 are then pierced through the fabric material 24. A fastening member in the form of a button 28 is adapted to be received over the pointed projections 22 and the device is then clamped into position so that the fabric 24 is pinched between the back surface of the button 28 and the head 18. 10 15

Referring more specifically to the button 28, 20 the outer surface may be made any size or shape and is intended primarily for ornamental purposes. The back surface of the button is provided with a closed wall 30 which acts as a guard for the pointed projections 22 and deforms the fabric 24 into the head 18, thereby more securely retaining the device in its position. Openings 32 have been provided in the back 30 to receive the pointed projections 22. Embossed projections 34 are formed in the back 30 which serve as a double function, namely, that of receiving the points of the projections 22 and pressing the fabric 24 into the head 18. Referring to Fig. 4, it will be apparent that when the device is secured to a fabric it is readily held in position and the hook 16 is inside the pocket for receiving an article, such as a key ring, to suspend the keys above the bottom of the pocket. It will also be understood that when a key ring, such as shown at 36, is on the hook 16, it will be impossible to move the hook through the guard 26, as shown in Fig. 2, to unfasten the device from the fabric 24.

The lower portion of the hook 16 has a greater width than the distance between the arms of the guard portions 26 adjacent that portion of the hook so that there is a resilient resistance tending to hold the hook in a position, as shown in Fig. 4, to prevent the key ring 36 from being accidentally removed from the hook. When the key ring is removed from the hook it will be understood that the thickness of the ring urges the hook forwardly against its resilient resistance. If desired the lower portion of the hook may have straight side walls and the arms of the guard 45 50 55

may extend inwardly to resiliently engage the hook, as shown in Fig. 7.

The pointed projections are normally positioned to enter the openings 32, but when the hook is swung to its normal position and forced between the arms of the guard portion the pointed projections are spread outwardly thereby frictionally retaining the parts together. Notches 25 may be provided in the sides of the pointed projections to engage the periphery of the openings.

While I have shown in Figs. 1 to 4, inclusive, an annular retaining member, it is to be understood that this may be of any shape or size, such as shown in Figs. 5 and 6. In Fig. 5, I have shown an oblong retaining member which is relatively narrow, and in Fig. 6, I have shown a diagonally shaped member.

I have shown in the preferred embodiment of the invention a device made of wire bent into the desired shape. However, if desired, the parts may be made from stampings. As an illustration of this, I have shown the hook member 16 and the head 18 formed from sheet metal having openings 38 to receive the coils 20 which form the pivot 14.

Various changes, including the size, shape and arrangement of parts, may be made without departing from the spirit of my invention, and it is my intention to cover by the appended claims such changes as may be reasonably included within the scope thereof.

What I claim is:

1. A supporting device comprising a hook member, a member having pointed projections pivotally mounted on said hook member, and a fastening member received on said pointed projections, said fastening member having spaced walls on the opposite sides of said pointed projections, one wall thereof having indentations in its inner

surface to receive the points of said pointed projections.

2. A supporting device comprising a hook member, a member having pointed projections pivotally mounted on said hook member and in frictional engagement with said hook member, and a fastening member received on said pointed projections, said fastening member having spaced walls on the opposite sides of said pointed projections, one wall thereof having indentations in its inner surface to receive the points of said pointed projections.

3. A supporting device comprising a member having pointed ends adapted to be inserted through a fabric material, a member pivotally supported on said first named member and at one side of the fabric material, and a fastening member on the opposite side of the fabric material received over the pointed ends, said fastening member having a substantially flat wall in engagement with the fabric material and provided with openings for receiving the pivoted ends, said flat wall being further provided with embossed projections to receive the pointed ends on one side thereof and to deform the fabric between the flat wall and the pivotally supported member on the opposite side of the fabric.

4. A key ring support comprising two members pivotally connected intermediate their ends, a hook portion and a head portion respectively at the opposite ends of one of said members, a guard portion and pointed projecting portions respectively at the opposite ends of the other of said members, a button having outer and inner walls, said inner wall being closed except for openings to receive said pointed projecting portions, said hook portion adapted to frictionally pass through said guard portion.

JOSEF C. TONKO.
